UNITED STATES PATENT OFFICE.

JOHN P. EDWARDS, OF NEW YORK, N. Y.

STATION-INDICATOR.

SPECIFICATION forming part of Letters Patent No. 251,707, dated January 3, 1882.

Application filed March 26, 1881. (No model.)

To all whom it may concern:

Be it known that I, JOHN P. EDWARDS, a citizen of the United States, residing in New York city, in the county and State of New York, have invented certain new and useful Improvements in Station-Indicators for Use on Railroad-Cars, of which the following is a specification.

My invention relates to that class of station-indicators in which the names are printed or painted on a long apron of woven fabric or other suitable material, which is unwound from one roller and wound upon another by the brakeman or other attendant at the proper intervals to indicate the successive stations. I have devised means for facilitating the operation, aiding the attendant to always ascertain what is indicated without looking at the face of the indicator, and for insuring the central placing of the name in the proper space at each change. I mount the rollers in a portable case and connect each roller by beveled gears to a separate shaft extending outward through the back of the case in convenient position to be operated by a key from the outside of the case. I place the indicator at either end of the car, with its face presented to the passengers and with its back toward the outside. The operating-shafts extend out through small holes in the car end, and are operated from outside.

The following is a description of what I consider the best means of carrying out the invention.

The accompanying drawings form a part of this specification.

Figure 1 is a front view with a portion of the face-plate removed, showing the interior gearing. Fig. 2 is a similar rear view. Fig. 3 is a vertical section, showing the apparatus in position on the wall of a car with its small window in position to allow of the conductor inspecting the interior, so as to correctly place the apron. Fig. 4 is a detailed view of parts.

Similar letters of reference indicate like parts in the figures.

A is a portion of the car; B, my portable case; C D, the rollers, and c d the operating-shafts, which connect by beveled-gear wheels c' d' and with beveled-gear wheels C' D' on their respective rollers. The shafts are turned

by the aid of small cranks c² d² on the outside of the car.

A small window, a, is made in the car end, which coincides in position with a corresponding aperture, b, in the back of the casing B. One or both of these apertures are glazed to defend against the weather; but the glass should be kept clean and bright to allow inspection by the attendant on the outside.

The apron E is wound on the rollers, so that by turning one to take up, the other will be turned of itself to deliver. G G are rods, of ash or elastic material, serving as slight brackets, resting against the shafts of the rollers. The pressure of each is controlled by a separate adjusting-screw, H, which is adjusted from time to time to secure a just sufficient resistance. Without this adjunct the mechanism is liable to turn too easily, especially as the device gets old, and to slacken the apron.

The inner face of the case is wholly or largely of glass. The name of the station is presented in large letters on the face side of the apron E, and is shown through the glass to the passengers in the car. The back of the apron carries on one edge the name of each station in small letters, and also a series of definite marks, I, which aid in leaving the apron in the correct position after each movement. Two distinct marks, J J, are made on the fixed frame-work adjacent to the edge of the apron. When the apron is shifted to announce the next station, the operator, standing outside, looks through the window b at the small name on the back of the apron and the corresponding mark I, and takes care to leave it with the mark I standing adjacent to and between the marks J J.

K and L are rollers, placed in the position represented, which have the effect to hold the apron closely pressing against the glass at the face of the case.

I attach much importance to the fact that the shafts c d are distinct and capable of being separately operated, and that they extend horizontally outward, so as to be easily operated from the platform of the car.

The invention avoids all necessity for special provisions for expansion and contraction of the apron. It allows the apron to be adjusted with ease in exact position under all circumstances,

traveling either way, and allows prompt and easy correction if through inadvertence or any cause the apron is turned too far.

Modifications may be made in the forms and proportions of the details. I propose to place the case B and its contents over the door or a window high enough to be seen over the heads of passengers who may be standing. In many cars a light or ventilator over the door or window may be brought to coincide with the window b in my casing and avoid making any special opening a in the car for the purpose. A bracket may be provided, when required, on which the attendant may step to attain sufficient height to turn the upper crank.

I claim as my invention—

In a station-indicator having an apron, E, mounted on independently-operated rollers C D, the bracket G, bearing against each roller, and adjusting-screws H, operating upon each wing of the bracket, in combination with said rollers and with means, *cd*, for operating them, substantially as set forth.

In testimony whereof I have hereunto set my hand, at New York city, this 24th day of March, 1881, in the presence of two subscribing witnesses.

J. P. EDWARDS.
